ELECTRICAL TELEPHONE TALK-LINE MONITORING SWITCH APPARATUS

Paul V. De Luca, Port Washington, and William V. Carney, Valley Stream, N.Y., assignors to Porta Systems Corp., Roslyn, N.Y.

Filed July 27, 1971, Ser. No. 166,655

Term of patent 14 years

Int. Cl. D14—03; D13—03
U.S. Cl. D26—14 A

FIG. 1 is a perspective view of the electrical telephone talk-line monitoring switch apparatus embodying our new design;

FIG. 2 is a front view of the apparatus depicted in FIG. 1;

FIG. 3 is a side view of the apparatus shown in FIG. 1;

FIG. 4 is a top plan view of the apparatus depicted in FIG. 1; and

FIG. 5 is a rear view of the electrical telephone talk-line monitoring switch apparatus depicted in FIG. 1.

We claim:

The ornamental design for an electrical telephone talk-line monitoring switch apparatus, substantially as shown.
